UNITED STATES PATENT OFFICE.

LOWELL W. SHIELDS, OF ROCHESTER, NEW YORK, ASSIGNOR TO HICKOK MANUFACTURING COMPANY, INC., OF ROCHESTER, NEW YORK, A CORPORATION OF NEW YORK.

DESIGN FOR A BELT SLIDE.

Application filed April 30, 1924. Serial No. 9,447. Term of patent 3½ years.

To all whom it may concern:

Be it known that I, LOWELL W. SHIELDS, a citizen of the United States, residing at Rochester, in the county of Monroe and State of New York, have invented a new, original, and ornamental Design for a Belt Slide, of which the following is a specification, reference being had to the accompanying drawing, forming part thereof.

In the drawing:

Fig. 1 is a front face view of the belt slide, showing my new design; and

Fig. 2 is an edge view of said belt slide.

I claim:

The ornamental design for a belt slide, as shown.

LOWELL W. SHIELDS.
